DESIGN FOR A PLATE

John L. Pasmantier, New York, N. Y.

Application September 25, 1936, Serial No. 65,015

Term of patent 3½ years

To all whom it may concern:

Be it known that I, John L. Pasmantier, a citizen of the United States, residing at New York, in the county of New York and State of New York, have invented a new, original, and ornamental Design for a Plate, of which the following is a specification, reference being had to the accompanying drawing, forming a part thereof.

The figure is a plan view of a plate showing my design. The ornamentation shown is continued throughout the border of the plate.

I claim:

The ornamental design for a plate, as shown and described.

JOHN L. PASMANTIER.
